CURTAIN STRETCHER

Stanley E. Maves, Freeport, Ill., and William M. Cushman, Washington, D. C., assignors to Western Newell Mfg. Co., Freeport, Ill., a corporation of Illinois

Application February 4, 1933. Serial No. 655,278

9 Claims. (Cl. 45—24)

The invention relates to a curtain stretcher, particularly a curtain stretcher in which no pins or similar means for attaching and holding the curtains while being dried and stretched are provided.

In the type of curtain stretchers using pins or similar means for the attaching and holding of the curtain, it will be found that the borders of the curtain will, after drying, assume a scalloped appearance which is objectionable, and that the material will have innumerable holes adjacent its edges which tend to hasten deterioration thereof.

In the type of curtain stretcher now in use in which no pins or similar elements are provided, great difficulty is experienced in the correct positioning of the curtain on the stretching rods in order that the curtain be evenly and not lopsidedly stretched.

It is one of the objects of the present invention to provide a pinless curtain stretcher on which the curtain may be, at all times, properly and evenly positioned.

It is another object of the invention to provide a curtain stretcher, the use of which simplifies the correct adjusting and positioning of the curtain on the stretching rods.

It is also a further object of the invention to provide a curtain stretcher which is efficient as to results and inexpensive to manufacture.

Further and other objects and advantages of the invention will be hereinafter apparent, and in the drawings.

Figure 1 is a perspective view of the curtain stretcher when in operative position;

Figure 2 is a sectional view of the curtain stretcher taken on the line 2—2 of Figure 1;

Figure 3 is a side view of one form of the curtain stretching rods;

Figure 4 is a side view of another form of the curtain stretching rods, and in addition shows the use of the flexible side members or connectors.

Figure 5 is a sectional view of the curtain stretching rods shown in Figure 4, when in operative position;

Figure 6 is a top view in part of the form of curtain stretching rod shown in Figure 4;

Figure 7 is a side view in part of still another form of the curtain stretching rods; and

Figure 8 is a sectional view of the curtain stretching rod disclosed in Figure 7.

Referring more particularly to the drawings, in which like numerals indicate like parts, the invention comprises two rods 10 and 11, the former

being for use at the top of the curtain and the latter, which is circumferentially the larger and heavier, being for use at the bottom of the curtain.

In the form of the invention illustrated in Figures 1, 2 and 3, the rods are disclosed as round and at their ends are provided with eyelets 12, having shanks 13 which are rigidly set therein.

In the form of the invention illustrated in Figures 4, 5 and 6, the transversely cross-sectional configuration of the rods are generally disclosed as pear-shaped, each having a substantially semi-circular portion 13' and a substantially tapered portion 14. At both ends of the rods there are provided eyelets 15, which are rotatably mounted in any suitable manner. In the construction here shown, portions of the rods adjacent the ends are cut away as at 16 and the shanks 17 of the eyelets 15 project into said cut-away portions through apertures in the rod ends and are held therein by means of the enlarged butts 18 of the said shanks.

In the form of the invention illustrated in Figures 7 and 8, the rods 19 are disclosed as round and eyelets 20 having relatively elongated shanks 21 are rotatably set in the ends thereof. On the said shanks are supported rods 22 having arms 23 at their ends which are screw threaded to receive the screw threaded portions 21' of said shanks. The rods 22 are of a substantially tapered configuration and have substantially concave bases 23 which fit the circular rods 19.

Graduations 24 having the proper indicia or numerals 25 are provided on the rods, the purpose of which is to facilitate correct measuring and positioning of the curtain on the rods, so that it will dry and stretch evenly, the four corners thereof being always equi-distant from the respective centers of the rods.

It will be observed that the said indicia or numerals for the graduations are arranged in ascending relation from the centers of the rods to their ends, so that each numeral of one series indicates the total distance from its adjacent graduation to the graduation adjacent the same numeral in the series at the other end of the rod.

By means of this system of graduations, the curtain may be quickly positioned by placing the four corners thereof at the four numerals indicating the desired or proper width, and the rods will, at all times, be exactly parallel to each other, and when the top rod is properly hung, there will exist perfect balance and an even dis-

tribution of tension on all portions of the curtain fabric.

In the form of the invention where the rods are round, as in Figures 1, 2 and 3, the graduations are placed parallel to the eyelets on both sides of the rods when they are hung in operative position and thereby may be easily observed by the user.

In the form of the invention as disclosed in Figures 4, 5 and 6, the graduations are on both sides of the substantially tapered portions 14. Due to the rotatably mounted eyelets, and as observed more particularly in Figure 5, the top rod, when properly positioned, will always have the tapered portion hanging downwardly and if the rod is hung above the user's head, the graduations being placed for reading when in this position can be readily observed. The bottom rod will be so held by the hem of the curtain that the tapered portion is pointing upwardly, and if the said rod is near the ground or floor, the graduations being placed for reading when in this position can be read without the necessity of stooping or leaning over by the user, and the desired adjustments of the curtain can be easily made.

In the form of the invention disclosed in Figures 7 and 8, it will be observed that the substantially tapered rods 22 are provided with the graduations and proper indicia or numerals.

Due to the rotatable mounting of the rods 22 relative to the rods 19, the said stretcher rods as a whole will function similarly to the form of the invention illustrated in Figures 4, 5 and 6.

In each form of the invention hereinbefore described, the stretcher rods adapted to be positioned at the bottom of the curtain are heavier than those adapted for use at the top of the curtain and the weight of the former is sufficient to provide the proper stretching of the curtain fabric.

Any suitable method may be used for positioning the top stretcher rod for operation, and, as shown in Figures 1 and 2, there is employed a hanger 26 comprising a lower hook portion 27 which is inserted through the eyelets at the ends of the rod and an upper and larger hook portion 28 which may be hung over a clothes line 29 or similar support.

If desired, the eyelets provided at the ends of the top stretcher rods may be supported simply by two ordinary hooks positioned the proper distance apart on a ceiling, wall or any other convenient place.

When the top stretcher rod has been threaded through the permanent or temporary hem, if need be, at the top of the curtain, the bottom and heavier stretcher rod is threaded through the lower permanent or temporary hem. The desired width of the curtain is obtained by positioning the four corners thereof at the identical graduations at each end of the rods respectively and when the curtain dries, it will be evenly stretched and will maintain thereafter the desired shape.

It will be obvious that were the top and bottom stretcher rods not positioned precisely alike in the hems of the curtains, particularly the bottom rod, there would result a curtain stretched in a lopsided and uneven manner. Furthermore, if the ends of the curtain were not positioned to provide the same width on the top and bottom rods, the curtain, when dried, would be stretched in a lopsided and uneven manner. With the use of the graduations and indicia or numerals

denoting the various widths on the stretcher rods, such a result is eliminated.

When necessary and desired, weights 30 having eyelets 31 may be attached to the outer ends of the lower stretcher rods to further stretch the curtain. The hanger 26 hereinbefore described may be used to connect the eyelets at the ends of the lower stretcher rods and the eyelets 31 of the said weights. Obviously other and various forms of weights and means of attachment to the stretcher rod eyelets may be used.

Referring to Figure 4 of the drawings, there will be observed additional means for correctly positioning and measuring the curtains on the stretcher rods. The feature to be described is particularly adaptable to curtains which are made of exceedingly stretchable material and which might be stretched to a greater degree than desired.

There are provided flexible members or connectors 32 comprising a suitable length of tape or similar flexible material. It will be noted that the said members are adjustable to the desired length between the attaching members 33 which in this instance and for illustrative purposes only, comprise loop portions 34 from which extend hook members, the latter cooperating with the eyelets 15. It is to be understood that the attaching members are capable of various forms which will perform the same functions.

A clip 35 is provided to hold the flexible members in their adjusted positions.

Graduations and the proper indicia or numerals are shown on the flexible members as at 36 and 37 respectively.

The operation of the flexible members is obvious and by means thereof the proper length of the curtain to be stretched can be easily determined by merely adjusting the said members to the desired lengths.

The flexible members or connectors are adapted for use with any of various forms of curtain rods shown.

With the use of the invention described, innumerable advantages over the type of stretcher rods now in use are evident.

The invention is susceptible of various forms and modifications which come within the scope of the appended claims.

We claim:

1. In a curtain stretcher, a supporting rod having a rotatable eyelet at each end and adapted for insertion into the upper hem of a curtain, a stretching rod adapted for insertion into the lower hem of the curtain, and graduations with indicia on said rods to facilitate similar positioning of the curtain thereon, said rods being substantially pear-shaped in cross-section and adapted to hang with their rounded portions facing outwardly from the center of the curtain.

2. In a curtain stretcher, a supporting rod having a rotatable eyelet at each end and adapted for insertion into the upper end of a curtain, a stretching rod adapted for insertion into the lower hem of the curtain, said rods being formed with substantially semi-circular portions and substantially tapered portions, and graduations with indicia arranged on said tapered portions to facilitate visibility thereof and an even positioning of the curtain on both rods, said tapered portions adapted to face each other when positioned in the hems of the curtain.

3. In a curtain stretcher, a supporting member and a stretching member adapted for insertion into the hems of a curtain, each comprising

- a rod having a second rod rotatably mounted at its ends, and means on said second rod for positioning the corners of said curtain equi-distantly from the respective centers of said rods.
- 5 4. In a curtain stretcher, a supporting member and a stretching member adapted for insertion into the hems of a curtain, each comprising a circular rod having a rotatable eyelet at each end and a second substantially triangular rod 10 mounted on the shanks of said eyelets, and means on said second rod for positioning the corners of said curtain equi-distantly from the respective centers of said rods.
5. In a curtain stretcher, a supporting member 15 and a stretching member adapted for insertion into the hems of a curtain, each comprising a circular rod having a rotatable eyelet at each end and a second substantially triangular rod mounted on the shanks of said eyelets, and 20 graduations having indicia on said second rod for positioning the corners of said curtain equi-distantly from the respective centers of said rods.
6. A curtain stretcher, a supporting member 25 and a stretching member adapted for insertion into the hems of a curtain, each comprising a substantially circular rod having a rotatable eyelet at each end and a substantially triangular rod having arms mounted on the shanks of said eyelets, and graduations having indicia on said 30 second rod for positioning the corners of said curtain equi-distantly from the respective centers of said rods.

7. In a curtain stretcher, a rod adapted for insertion into the upper hem of a curtain, a rod adapted for insertion into the lower hem of the curtain, means on said rods for positioning the corners of said curtain and measuring the width thereof, and flexible means between the rods for measuring the length of the curtain and supporting the lowermost rod in adjusted position.
8. In a curtain stretcher, a rod adapted for insertion into the upper hem of a curtain, a rod adapted for insertion into the lower hem of a curtain, means on said rod for positioning the corners of said curtain and measuring the width thereof, and adjustable flexible tape-like members between the outer ends of the rods for measuring the length of the curtain and supporting the lowermost rod in adjusted position.
